UNITED STATES PATENT OFFICE.

JOSÉ M. ALMEDIA, OF SHOSHONE, IDAHO.

BAG-FASTENER.

1,401,854.

Specification of Letters Patent. Patented Dec. 27, 1921.

Application filed June 7, 1918. Serial No. 238,684.

To all whom it may concern:

Be it known that I, JOSÉ M. ALMEDIA, a citizen of the United States, residing at Shoshone, in the county of Lincoln and State of Idaho, have invented certain new and useful Improvements in Bag-Fasteners; and I do hereby declare the following to be a full, clear, and exact description of the invention, such as will enable others skilled in the art to which it appertains to make and use the same.

My invention relates to improvements in locking devices for bags.

An important object of this invention is to provide a locking device for mail bags and the like comprising an attachment to be secured to the upper portion of the bag, to lock the same securely and prevent access to the bag by unauthorized persons.

20 A further object of the invention is to provide a locking device for mail bags and the like comprising a pair of arms adapted to encircle the bag at its upper portion, a centrally disposed rod adapted to extend 25 through alining apertures in the upper portion of the bag, and novel locking means for the arms encircling the bag.

30 A further object of the invention is to provide a device of the character described, which is highly efficient in use, reliable, of highly simplified construction and cheap to manufacture.

Other objects and advantages of the invention will be apparent during the course 35 of the following description.

In the accompanying drawings forming a part of this specification and in which like numerals are employed to designate like parts throughout the same,

40 Figure 1 is a plan view of a locking device embodied in my invention, showing the same applied to a bag and parts thereof being cut away,

45 Fig. 2 is a plan view of the same, showing the device open,

Fig. 3 is a side elevation of the same applied to a bag, and,

Fig. 4 is a transverse section taken on line 4-4 of Fig. 1.

50 In the drawings, wherein for the purpose of illustration is shown the preferred embodiment of my invention, the numeral 5 designates an approximately semi-circular arm having formed integrally therewith a centrally disposed rod 6, said rod having a reduced end portion 7. A second arm des-

gnated by the numeral 8 and pivotally secured to the first named arm as at 9 is semi-circular in shape and is provided with a slot 10 adapted for the reception of the reduced end portion 7 of the rod 6. That portion of the arm 8 having the slot 10 therein is increased in thickness and said slot 10 has its walls convexed to provide an enlarged entrance opening therein for the reception of the reduced portion 7 of the rod 6.

As clearly shown in Fig. 1, a mail bag 11 possessed of the usual degree of pliability is provided in its upper portion with apertures 12. The apertures 12 are provided with circular reinforcements 13. The upper portion of the bag is adapted to be folded or crimped upon itself, to form a plurality of U-shaped section, thus alining the apertures 12 for the reception of the rod 6.

An apertured ear 14 formed on one side of the arm 5 and disposed centrally thereof is adapted for the reception of a pivot 15 which serves to secure a handle 16 thereto.

As more clearly shown in Fig. 1, a lock 17 formed on one end portion of the arm 5 and designated by the numeral 17 is adapted to coact with a locking bar 18 formed on one end of the arm 8. A pivoted pawl 19 arranged within the lock 17 is actuated by a coiled spring 20. The forward end of the pivoted pawl 19 is adapted to normally contact with teeth 21 formed on the outer side of the locking bar 18. The lock 17 is provided with a keyhole 22 adapted for the reception of a key. With reference to Fig. 1, it will be apparent that the key in turning within the keyhole 22, will contact with the rear portion of the pivoted pawl 19, thus disengaging the same from the teeth 21 of the locking bar 18. The rear face of the block 17 may be provided with means for receiving an address card showing the destination of the mail bag.

In attaching my improved locking device to a bag, it will be apparent that the rod 6 is passed through the alining apertures 12. The reduced end portion 7 will extend through the opening 10, thus preventing the bag from being removed from the rod when the locking bar 18 is engaged by the lock.

While I have shown and described the preferred embodiment of my invention, it is understood that I may make such minor changes in arrangement and construction of parts, as will remain within the spirit of

2
the invention and the scope of the appended section, and a lock for the frame sections
claim. at the end of one of the sections adapted to
bear against a wall.

Having thus described my invention, In testimony whereof I affix my signature
what I claim is:

- 5 A bag fastener comprising two frame sections pivotally connected together, a
handle on and extending above one of the frame sections, a tongue extending from one
of the frame sections intermediate the ends
10 thereof and across and into the other frame

Witnesses:
